[57] CLAIM

The ornamental design for a combined drapery rod and bracket, as shown and described.

DESCRIPTION

FIG. 1 is a perspective view of a combined drapery rod and bracket showing my new design;

FIG. 2 is a front elevational view of a drapery rod shown separately for clarity of illustration only, the rear view being a mirror image;

FIG. 3 is a bottom plan view thereof, the top being a mirror image;

FIG. 4 is a side elevational view thereof, on an enlarged scale;

FIG. 5 is a front elevational view of the bracket, shown separately for clarity of illustration only;

FIG. 6 is a side elevational view thereof, on an enlarged scale, the other side being a mirror image;

FIG. 7 is a bottom plan view thereof;

FIG. 8 is a top plan view thereof.

FIG. 1.

FIG. 2.

FIG. 3.

FIG. 4.

FIG. 8.

FIG. 5.

FIG. 6.

FIG. 7.
